3 Claims. (Cl. 137—118)

The invention relates to fluid power transmission, and applies to the actuation of two fluid motors from a single power source.

More particularly, the invention pertains to such applications where two fluid motors must be driven at closely proportional speeds over a range of speeds and under conditions involving unequal loads on the two motors. It is intended for such systems in which a variable quantity of fluid is delivered at the power source, and in which the operating pressure depends upon the pressure of the more heavily loaded of the two motors. These conditions require a type of flow divider control which will maintain a predetermined division of fluid flowing to the motors regardless of varying resistances in one or the other of the two motors.

In is the object of this invention to attain an accurately proportionate division of fluid from this power source to the fluid motors over a considerable range of speeds, in a pulsation free flow, independent of load variations in either of the two fluid motors, and at operating pressures not substantially in excess of the fluid motor operating pressures. The principle and the advantages of the present invention are described in greater detail in the following specification in which

FIG. 1 is a cross sectional view of the flow divider, and FIG. 2 is a plan view of the inlet side of the same.

Referring now to FIG. 1, the body 11 is provided with inlet port 12 and outlet ports 13 and 14. Inlet port 12 leads to the central thru bore 15 which at the inlet end is fitted with bushing 16 and at the opposite end with bushing 17. Bushings 16 and 17 are axially held in position by the snap ring 18 and the sealing plug 19 respectively. A pin and groove lock, not shown in the drawing, in the head of bushing 16 fixes its angular position. Sealing plug 19 is held against the head of bushing 17 by the cover 20. Bushings 16 and 17 serve as support for the valve spool 21 whose diameter has one half the cross sectional area of the bore 15. Valve spool 21 is provided with a shoulder 22 which is somewhat smaller in diameter than bore 15. Shoulder 22 serves as a stop for spool 21 when the latter is urged against bushing 16 by the spring 23, and it also serves as a shoulder for piston 24 which is slidably fitted in bore 15 and over spool 21 in the space formed between bushings 16 and 17. Bushing 16 has two radial orifices 25 and 26 leading to hydrostats 27 and 28 respectively. The size of these orifices is governed by the edge at the end of spool 21, and may be anything between the closed position shown and a full opening. Hydrostats 27 and 28 establish the connection between orifices 25 and 26, and the outlet ports 13 and 14 by way of annuli 29 and 30 respectively. Each of the hydrostats embodies a spring biased piston fitted slidably to a chamber adjacent to and in connection with orifice 25 or 26. The outer ends of the hydrostat pistons are in communication with the inlet port by way of passages 31, 32, 33, and 34. Passages 32 and 34 also are in unidirectional communication with the annuli 29 and 30 thru check valves 35 and 36 which permit flow in the direction of the inlet port only. For a condition not involving any back pressure in either of the outlet ports, the operation of the flow divider proceeds in the following manner:

Fluid entering the inlet port first flows to the outer ends of the hydrostats, and forces the spring loaded pistons inwardly, thus sealing the passages between orifices

2

25 and 26, and their respective outlet ports. Further admission of fluid causes a rise in pressure until the value set by spring 23 is reached, at which point spool 21 is displaced axially to the extent that some fluid is allowed to pass thru orifices 25 and 26 into the hydrostats. As this is taking place, the hydrostat pistons will begin to move outwardly as soon as fluid pressure on the spring side of the pistons reaches a value equal to the inlet pressure minus the pressure equivalent of their springs. 10 The outward movement of the hydrostat pistons continues to the joint where just enough fluid is allowed to escape into the annuli and the outlet ports thru the metering notches 37 that this pressure differential between the inlet pressure and the pressure on the spring side of the hydrostat pistons is maintained. If we now assume, for instance, the pressure equivalent of spring 23 to be 50 p.s.i., and that of the hydrostat springs to be 30 p.s.i., it follows that for any given flow within the capacity of the unit the fluid pressure inside the hydrostat chamber will be maintained at 30 p.s.i. below the inlet pressure, and that there will be a pressure drop from the hydrostats to the outlet ports of 20 p.s.i. Provided that both orifices 25 and 26 are of the same size and shape, it becomes evident that the flow thru the two orifices is equal because of a constant and equal pressure drop maintained across the orifices.

Considering now a condition where a resistance to flow exists in outlet 13 which requires a pressure of 200 p.s.i. to overcome it, and no resistance in outlet 14, we assume, 30 as in the preceding case, that the pressure equivalent of spring 23 is 50 p.s.i. at the point of opening of orifices 25 and 26, and that the hydrostat springs will amount to 30 p.s.i. at the cracking point of the hydrostats. Fluid entering the unit will again first close the hydrostats, and 35 then, as the pressure rises to 50 p.s.i., begin to open orifices 25 and 26. As soon as the pressure in the hydrostat chambers reaches 20 p.s.i. (50—30), the hydrostats tend to open. Any flow into port 13, however, will immediately begin to build up pressure in that port, since a pressure of 200 p.s.i. must be reached before any appreciable flow can take place. But any pressure build up in port 13 is transmitted at once to piston 24 thru passage 40, thus assisting spring 23, and helping to maintain a pressure difference of 50 p.s.i. between port 13 and the inlet port. Consequently, flow across orifice 25 can 45 take place only after the pressure in the inlet port has climbed to 250 p.s.i. Fluid going to outlet 13 thus is at a pressure of 250 p.s.i. in the inlet port, 220 p.s.i. in the hydrostat chamber, and 200 p.s.i. in port 13. On the way to port 14, fluid pressure drops from 250 p.s.i. to 220 p.s.i. from inlet to hydrostat chamber, and from there to 0 p.s.i. in port 14. In spite of the pressure difference existing 50 between the two outlet ports, the flow over the two orifices remains equal because of the constant and equal pressure drop maintained.

If now a resistance develops in outlet 14, the pressure in this port is transmitted simultaneously to the spring end of spool 21 thru passage 39, and to the side of piston 24 contacting shoulder 22 thru passage 38. Since piston 24 and spool 21 are equal in cross sectional area, the forces exerted on spool 21 by this pressure rise are equal and opposite, and cancel each other out as long as the pressure in port 14 is below that of port 13. As soon as fluid pressure in port 14 begins to exceed that of port 13, piston 24 is pushed against bushing 17, and the pressure in port 14 begins to act effectively against the spring end of spool 21. If now the pressure in port 14 again drops below that of port 13, pressure in the latter port forces piston 24 away from bushing 17 and against shoulder 22, thus returning the pressure control to port 13. The separating of piston 24 from shoulder 22 or from the upper end of bushing 17 during the change of

the higher outlet pressure from one port to the other requires that the contact surfaces on both ends of piston 24 be so constructed as to permit ready access of the fluid medium thereto, a detail which is not shown in the drawing.

Thus it may be seen that the present invention permits an accurate division of a variable fluid flow to two outlets at an inlet pressure determined by and not substantially greater than the higher of the two outlet pressures. An unequal but proportionate division of flow may be obtained by the incorporation of suitable orifices and by employing unequal but constant pressure drops across the metering orifices.

Check valves 35 and 36 between the annuli of the hydrostats and passages 32 and 34 respectively provide for a return flow from the outlet ports to the inlet port.

What I claim is:

1. A valve structure comprising, in combination, a body, an inlet port and two outlet ports on said body, a movable spool governing two variable orifices in said body between said inlet and outlet ports, fluid pressure responsive means for maintaining a constant pressure drop across each one of said two orifices, spring means for biasing said spool to keep the said orifices closed against the pressure of incoming fluid, said spring means being of greater magnitude than the said pressure drop across either of the orifices, and fluid pressure responsive means acting upon said movable spool so as to add to the said spring means any pressure increase in the one of the two outlet ports having the higher fluid pressure of the two.

2. In a flow dividing valve, the combination of a body having one inlet port and two outlet ports, a movable spool governing two variable orifices in said body between said inlet and outlet ports, fluid pressure responsive means for maintaining a constant pressure drop across each one of said two orifices, spring means for biasing said spool to reduce the size of the said two orifices against the pressure of incoming fluid, said spring means being of greater magnitude than the said pressure drops across either of the orifices, fluid pressure responsive means acting upon said movable spool so as to add to the said spring means any pressure increase occurring in the one of the two outlet ports having the higher fluid pressure of the two ports,

and two check valves, one each being interposed between an outlet port and the inlet port so as to permit a direct return flow from the outlet ports to the inlet port.

3. In a flow dividing valve, the combination of a body having one inlet port and two outlet ports, a chamber formed in said body adjacent to the inlet port, means in said chamber forming two bores of minor diameter and of like size, one at each end, and a major diameter bore between the two bores of minor diameter, said major diameter bore having twice the cross sectional area of one of the minor diameter bores, said chamber being open at one end to the inlet port of the body and being closed at the opposite end, two openings in the minor diameter bore of the chamber near the inlet port, each of said openings leading to control valve means for maintaining a constant pressure drop across each of said openings, a spool slidably fitted to the minor diameter bores of said chamber, said spool having such axial freedom of movement as to be capable of opening and closing the said openings in the minor diameter bore near the inlet port, means forming a shoulder on said spool somewhat smaller than the major diameter bore of said chamber and acting as an axial stop for the spool in the direction of the inlet port, spring means disposed in the closed end of said chamber to bias said spool in the direction toward the inlet port, a movable sleeve type piston fitted slidably to the major diameter bore of the said chamber and fitted slidably over the said spool on the side of said shoulder away from the inlet port, a fluid passage from one of the outlet ports to the major diameter bore of said chamber entering on the side of said piston away from the inlet port, a fluid passage from the other of the outlet ports to the major diameter bore of said chamber entering on the side of the piston toward the inlet port, and a second fluid passage from this latter outlet port to the closed end of the minor diameter bore of said chamber.
